AUTOMATIC PUMP

Pruitt L. Clements, Pauls Valley, Okla.

Application February 19, 1951, Serial No. 211,651

3 Claims. (Cl. 103—23)

1

This invention relates to an automatic pump, and more particularly to an automatic pump for oil wells.

The object of the invention is to provide a pump which will pump oil from an oil well until the level of oil in the well drops below a certain level, after which the pump will temporarily stop operating until the level of oil in the well rises above a predetermined level.

Another object of the invention is to provide an automatic oil well pump which is especially suitable for pumping oil from small wells, the operation of the pump automatically stopping after the level of oil in the well recedes too much so that an attendant is not required to disconnect the pump, the assembly of the present invention adapted to be used for simultaneously pumping oil from a plurality of adjacent wells, the pump of the present invention effecting a saving in labor costs as well as enabling a higher percentage of oil recovery from small wells which ordinarily would not be worked.

A further object of the invention is to provide an oil well pumping system which is extremely simple and inexpensive to manufacture.

Other objects and advantages will be apparent during the course of the following description.

In the accompanying drawings, forming a part of this application, and in which like numerals are used to designate like parts throughout the same.

Figure 1 is a side elevational view of the pump assembly, constructed according to the present invention, and showing the position of the parts when the pump is not operating.

Figure 2 is a fragmentary side elevational view showing the position of the parts when the hook member is being raised into operative position.

Figure 3 is a fragmentary side elevational view, showing the position of the parts when the pump is operating.

Figure 4 is a fragmentary side elevational view showing the timing mechanism.

Figure 5 is a sectional view taken on the line 5—5 of Figure 4.

Figure 6 is a sectional view taken on the line 6—6 of Figure 4.

Figure 7 is an enlarged top plan view of the assembly of Figure 4.

Figure 8 is a sectional view taken on the line 8—8 of Figure 4.

Figure 9 is an enlarged sectional view taken on the line 9—9 of Figure 1.

Figure 10 is an enlarged elevational view of the brake.

Figure 11 is a sectional view taken on the line 11—11 of Figure 10.

2

Figure 12 is an enlarged side elevational view, with parts broken away and in section showing the operation of the crank.

Figure 13 is a view similar to Figure 12, but showing the position of the parts when the pump is operating.

Figure 14 is a top plan view of the assembly of Figure 13.

Figure 15 is an end elevational view of the crank.

Referring in detail to the drawings, the numeral 30 designates a vertically disposed hollow standard which may be made of a suitable piece of pipe, Figures 12, 13 and 14. The standard 30 has its lower end embedded in a concrete base 31, and the standard 30 is provided with a pair of opposed slots 32 and 33. A crank 34 is pivotally mounted in the standard 30 by means of a pin 31, and the crank 34 comprises a first bracket 35 which is connected to a second bracket 36 by a pin 38.

The bracket 35 is provided with a plurality of spaced openings 39 adjacent one end, and the bar 40 is adapted to have one of its ends arranged in engagement with one of the openings 39. The other bracket 36 has a cam member 41 pivotally connected thereto by means of a pin 43, and a coil spring 42 is interposed between the cam member 41 and the bracket 36 for a purpose to be later described.

The other end of the bar 40 is pivotally connected to a movable lever 44, the lever 44 being provided with a plurality of spaced openings 45 and one of these openings 45 is adapted to be engaged by the bar 40. The lever 44 can be adjusted as to height or elevation, since the lever 44 is telescopically arranged in a sleeve 46, the lower end of the sleeve 46 being pivotally connected to ears 47 by a pin 48, Figure 1. The ears 47 may be embedded in a concrete base 49. A set screw 50 is provided for maintaining the lever 44 immobile in its various adjusted positions in the sleeve 46.

Slidably supported in the upper end of the standard 30 is a horizontally disposed arm 51. An elongated rod 52 has one of its ends connected to an end of the arm 51, and the other end of the rod 52 is adapted to be connected to a conventional oil well pump. The rod 52 has sufficient length, so that when the load on the pump decreases, as when the level of oil in the well falls below a predetermined level, the rod 52 will sway or bend downward slightly. Mounted on the rod 52 is a dog or block 53, Figure 1, and when the rod 52 sways downwardly to the position shown in Figure 1, as when the level of oil in the well decreases sufficiently, the block 53 will move down-

5 10 15 20 25 30 35 40 45 50 55

wardly and engage the upper end of the lever 44 to thereby move the bar 40 and crank 34 from the position shown in Figure 13 to the position shown in Figure 12.

The arm 51 is provided with a notch 54, Figure 13, in its lower surface, and the notch 54 is adapted to be selectively engaged by a keeper 55, the keeper 55 being urged upwardly into engagement with the notch 54 when the crank 34 pivots from the position shown in Figure 13 to the position shown in Figure 12. The keeper 55 is slidably maintained in its proper place by means of a pair of L-shaped guide members 56, Figure 14. A pair of ears 57 are secured to one end of the arm 51 by suitable securing elements such as rivets 58, and a pin 59 pivotally connects one end of a hook member 60 to the ears 57. The hook member 60 is provided with a hook 61 for a purpose to be later described. Thus, as shown in Figures 12 and 13, the hook member 60 can pivot about the pin 59.

A reciprocating link 62 is provided with an offset portion 63, Figure 1, and a clamp 64 connects one end of the link 62 to a ring 65. The ring 65 is adapted to selectively engage the hook 61 when the hook 61 is in its raised position as shown in Figure 2. The other end of the link 62 is adapted to be connected to a conventional engine which may be arranged in a powerhouse (not shown).

The offset portion 63 of the link 62 is adapted to engage an upright 66 on its return stroke, the lower end of the upright 66 being pivotally connected to ears 67 by a pin 68. The ears 67 are embedded or otherwise secured in a base 69. The upright 66 is provided with a plurality of spaced openings 70, Figure 1. The link 62 is guided by a guide member 73 which is mounted on the upper end of a pole 71, and the pole 71 can have its lower end embedded in the concrete base 72.

The assembly of the present invention further includes a timing mechanism which is indicated generally by the numeral 74, Figures 4, 7 and 8. The timing mechanism 74 includes a first gear wheel 75, and a second gear wheel 76. Secured to the first gear wheel 75 by screws or rivets 78, is a lug 77 which is provided with several teeth thereon. The teeth of the lug 77 are adapted to engage the teeth on the gear wheel 76 so that rotation of the gear wheel 75 will cause rotation of the gear wheel 76. The second gear wheel 76 is rotatably connected to a vertically disposed plate 80 by means of a pin 79, while the first gear wheel 75 is rotatably connected to the plate 80 by a pin 81, and the plate 80 extends upwardly from a horizontally disposed plate 83 which is secured to a concrete base 82.

A roller 84 is secured to the gear wheel 76, Figures 4 and 8. The roller 84 is adapted to engage a movable finger 85, Figure 2, and the finger 85 has one end pivotally connected to a post 87 by means of a pin 86. Secured to the other end of the finger 85 is a collar 88, and the collar 88 forms part of a support member 91. The support member 91 further includes a stem 89 that is slidably arranged in the collar or casing 88, and mounted on the upper end of the stem 89 is a seat 90 which is adapted to engage the lower surface of the hook member 60. A set screw 92 is provided for maintaining the stem 89 immobile in its various adjusted positions in the collar 88.

An ear 93 has its lower end pivotally connected to the plate 80, and the upper end of the ear 93 is connected to one end of a brace 94, the other end of the brace 94 being arranged in engagement with one of the openings 70 in the upright

66, Figure 1. Carried by the ear 93 is a pawl 95, and the pawl 95 is adapted to engage the teeth on the gear wheel 75, so that as the brace 94 moves back and forth due to the movement of the upright 66 or link 62, the gear wheel 75 will be rotated. A dog 96 is pivotally connected to the plate 80, and the dog 96 also engages the teeth on the gear wheel 75 for preventing this gear wheel from rotating in the wrong direction.

10 A brake is provided for preventing accidental rotation of the second gear wheel 76, and this brake is shown in detail in Figures 10 and 11. The brake includes a body member 97 that is secured to the plate 80 by means of set screws 98, and a cam 99 is pivotally connected to the body member 97 by means of a pin 100. A coil spring 101 is interposed between the plate 80 and the cam 99, and the coil spring 101 normally urges the cam member 99 into frictional engagement with the gear wheel 76.

From the foregoing, it will be seen that an assembly has been provided which will automatically operate the pumping equipment of oil wells. The assembly is so constructed that the oil will be pumped from the wells until the level of oil recedes below a certain level, and then the pump will be automatically stopped until the level of oil in the well again rises. The rod 52 is adapted to be connected to a conventional pump jack which may be arranged at the top or head of the oil well, while the link 62 is adapted to be connected to a conventional engine which may be arranged in a powerhouse. The assembly of the present invention is especially suitable for operating wells that produce only a small amount of oil, such as from one-half to thirty barrels of oil per twenty-four hours. These small oil wells are presently operated manually so that at the present time when the oil in the well becomes exhausted, or when it drops below a certain level, an attendant must be at the central power station to disengage the hook member 60 from the ring 65 until the well bore again fills up with fluid. Then, it has been the practice to have the attendant again connect the hook member 60 to the ring 65 when the fluid level in the well bore increases again.

By means of the assembly of the present invention, one or more wells can be operated without the attention of an attendant, since when the fluid in the well bore drops sufficiently, the operation of the pump jack for that particular well will be stopped. Thus, the labor costs for operating these small wells will be greatly reduced. Also, it will not be necessary to abandon these wells which produce only a small quantity of oil.

In operation, the link 62 is reciprocated back and forth by means of the conventional engine in the powerhouse, and the link 62 normally moves about twenty-four inches at the rate of about ten strokes per minute. Each time the link 62 moves back on its return stroke, the offset portion 63 will engage the upright 66 to thereby pivot the upright, and this movement of the upright 66 will cause the brace 94 and ear 93 to move. This pivotal movement of the ear 93 causes the gear wheel 75 to rotate, since the pawl 95 engages the teeth on the gear wheel 75. The gear wheel 75 is of such a size that it will make a complete revolution every five minutes, and it will be seen that the toothed lug 77 which is carried by the gear wheel 75 will also make a complete revolution every five minutes. Thus, the toothed lug 77 will engage the second gear wheel

76 once every five minutes to thereby rotate the gear wheel 76 so that the gear wheel 76 will make one complete revolution every two hundred and fifty minutes and this is the time during which the pump jack will not operate. A greater number of the toothed lugs 77 can be provided if it is desired to reduce the time at which the pump jack is not operating.

As the gear wheel 76 is rotated, the roller 84 will move to thereby raise the finger 85, the finger 85 resting on the roller 84. This upward pivotal movement of the finger 85 will raise the support member 91 so that the hook member 60 can be raised or positioned in such a manner as to be engaged by the ring 65. During this operation, the rod 52 will be pulled taut due to increased oil in the oil well, and the keeper 55 will drop below the notch 54 and the pump jack will again be operated.

The brake mechanism including the members 97 and 99 prevents accidental rotation of the gear wheel 76.

When the well bore is full of oil, the rod 52 is held taut since the full load of fluid causes the rod 52 to run in a horizontal or straight line. As the fluid level in the bore lowers, the pumping device in the well bore will not pick up a full load of oil or fluid, and when the pumping device engages the top of the fluid which gradually is getting lower and lower, and when the well bore is pumped dry, the rod 52 will sway several inches so that the block 53 will engage the upper end of the lever 45. This will cause a pivotal movement of the crank 34 so that the keeper 55 will be moved up into engagement with the notch 54. This will stop action of the pump jack since the arm 51 or rod 52 will not be able to reciprocate. Then, the hook member 60 will be able to pivot downwardly about the pin 59 as shown in Figure 1. Thus, the pump jack will not operate for four hours or less (this time can be varied as desired), and then the ring 65 and hook 61 will again be engaged with each other so that pumping operations will start and continue until fluid in the well bore is exhausted and then the previously described operations will be repeated. The spring 42 enables the cam member 41 to flex sufficiently in the event that the keeper 55 is urged upwardly against the lower surface of the arm 51 before the notch 54 is in the correct position. As the parts are shown in Figure 1, the pump jack is not operating. It is to be noted, that when the fluid level in the well bore is too low, the pump jack will not pick-up a full load of oil so that the rod 52 will sway or bend slightly. When the rod 52 sways, the block 53 will engage the upper end of the lever 44. This causes pivotal movement of the crank 34 so that the crank 34 moves from the position shown in Figure 13 to the position shown in Figure 12 and this pivotal movement of the crank will cause the keeper 55 to be seated in the notch 54 so that the arm 51 will remain stationary and so will the rod 52 remain stationary whereby further operation of the pump jack will be prevented.

The previously described timing mechanism is constructed so that at predetermined intervals the finger 85 will be raised to thereby lift the support member 91 whereby the hook member 60 will be raised upwardly as shown in Figure 2 so that the reciprocating ring 65 can engage the hook member 60. Then, the reciprocating link 62 will cause the arm 51 and rod 52 to reciprocate whereby the pump jack will be operated until the level of oil in the well is again lowered.

It will be seen that eventually the support member 91 will move out of engagement with the hook member 60 so that with the keeper 55 engaged in the notch 54, the hook member 60 will be able to pivot to the position shown in Figure 12 whereby the hook 61 and ring 65 will become disengaged when the oil in the well drops below a certain level. By arranging the brace 94 in engagement with different of the openings 70 in the upright 66, the timing mechanism can be varied to operate at different intervals. With the parts shown in Figure 3, the pump jack will be operated to pump oil from the oil well.

Having described the invention, what is claimed as new is:

1. In an automatic oil pumping system, a vertically disposed standard, a crank pivotally connected to said standard, a bar having one end connected to said crank, a movable lever connected to the other end of said bar, a horizontally disposed arm slidably supported by said standard, a rod having one end connected to said arm and its other end adapted to be connected to an oil well pump jack, a block mounted on said rod for engaging the upper end of said lever when said rod sways as a result of a decreasing load of oil in the well, a hook member pivotally connected to said arm, a reciprocating link provided with an offset portion and having one end adapted to be connected to an engine, a ring connected to the other end of said link for engagement with said hook member, a movable upright adapted to be engaged by said offset portion, and a timing mechanism for selectively raising said hook member to be engaged by said ring, said timing mechanism comprising a vertically disposed plate, a first gear wheel rotatably connected to said plate, a second gear wheel rotatably connected to said plate, a toothed lug carried by said first gear wheel for engaging said second gear wheel, a roller connected to said second gear wheel, a movable finger adapted to be engaged by said roller, an adjustable support member connected to said finger for engaging said hook member, and means for selectively rotating said first gear wheel upon pivotal movement of said upright.

2. In an automatic oil pumping system, a vertically disposed standard, a crank pivotally connected to said standard, a bar having one end connected to said crank, a movable lever connected to the other end of said bar, a horizontally disposed arm slidably supported by said standard, a rod having one end connected to said arm and its other end adapted to be connected to an oil well pump jack, a block mounted on said rod for engaging the upper end of said lever when said rod sways as a result of a decreasing load of oil in the well, a hook member pivotally connected to said arm, a reciprocating link provided with an offset portion and having one end adapted to be connected to an engine, a ring connected to the other end of said link for engagement with said hook member, a movable upright adapted to be engaged by said offset portion, and a timing mechanism for selectively raising said hook member to be engaged by said ring, said timing mechanism comprising a vertically disposed plate, a first gear wheel rotatably connected to said plate, a second gear wheel rotatably connected to said plate, a toothed lug carried by said first gear wheel for engaging said second gear wheel, a roller connected to said second gear wheel, a movable finger adapted to be engaged by said roller, an adjustable support member connected to said finger for engaging said hook member, and means for selectively rotating said first gear wheel upon pivotal movement of said upright.

member connected to said finger for engaging said hook member, and means for selectively rotating said first gear wheel upon pivotal movement of said upright, said last named means comprising an ear pivotally connected to said plate, a brace connecting said ear to said upright, and a pawl carried by said ear for engaging said first gear wheel.

3. The apparatus as described in claim 2 and further including a brake for controlling rotation of said second gear wheel.

PRUITTE L. CLEMENTS.
